(74) Attorney, Agent, or Firm—Damian Porcari

(57) CLAIM

The ornamental design for a vehicle grille, as shown and described in FIGS. 1-5.

DESCRIPTION

FIG. 1 is a front perspective view of a vehicle grille attached to a vehicle, no part of the vehicle is claimed;

FIG. 2 is a perspective view of the vehicle grille;

FIG. 3 is a front view of the vehicle grille;

FIG. 4 is a left side view of the vehicle grille (the right side view is a mirror of the left side view and is not shown); and,

FIG. 5 is a top view of the vehicle grille.

The broken lines shown throughout the drawing are for illustrative purposes only and form no part of the claimed design.

1 Claim, 5 Drawing Sheets
